CLAIM

The ornamental design for a dispensing orifice, as shown and described.

DESCRIPTION

FIG. 1 is a top plan view of a dispensing orifice, showing our new design;

FIG. 2 is a top plan view thereof, shown in a position of use with an exemplary lid;

FIG. 3 is a top perspective view thereof; and,

FIG. 4 is a top perspective view thereof, shown further in a position of use with an exemplary container;

FIG. 5 is a top plan view thereof, shown in a position of use with another exemplary lid;

FIG. 6 is a front plan view thereof;

FIG. 7 is a rear plan view thereof;

FIG. 8 is a first side plan view thereof; and,

FIG. 9 is a second side plan view thereof.

(Continued)

The broken lines are shown for the purpose of illustrating environmental subject matter of an exemplary lid and container that form no part of the claimed design.

1 Claim, 7 Drawing Sheets
